ROTARY WING AIRCRAFT OR SIMILAR ARTICLE

Eugene M. Gluhareff, 18518 S. Broadway,
Gardena, Calif. 90247

Filed Nov. 25, 1968, Ser. No. 14,614

Term of patent 14 years

Int. Cl. D12—07

U.S. Cl. D71—1

*FIG. 4.**FIG. 5.**FIG. 6.*FIG. 1 is a perspective view of a rotary wing aircraft or similar article showing my new design;

FIG. 2 is a top plan view;

FIG. 3 is a side elevational view showing the side opposite that shown in FIG. 1;

FIG. 4 is a perspective view showing another embodiment of my design wherein the body of the article is generally oblong;

FIG. 5 is a top plan view of the embodiment shown in FIG. 4; and

FIG. 6 is a side elevational view showing the side opposite that shown in FIG. 4.

I claim:

The ornamental design for a rotary wing aircraft or similar article, as shown.
